(57) **CLAIM**

I claim the ornamental design for a tubular reactor, as shown and described.

DESCRIPTION

FIG. 1 is a front, top and left side perspective view of a tubular reactor showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof; and,

FIG. 8 is a cross-sectional view taken along line 8-8 in FIG. 3.

The dashed-dot-dashed lines represent the boundary lines of the claimed design. The broken lines are included for the purpose of illustrating portions of the article that form no part of the claimed design.
